UNITED STATES PATENT OFFICE.

ANDREWS ALLEN, OF GLENCOE, ILLINOIS.

DRAFT MECHANISM.

Application filed March 13, 1922. Serial No. 543,150.

My invention relates to draft mechanism for mine cars and has for its particular object the provision of a draft means which automatically positions itself in coupling relation with a co-operating draft member secured to another car so that a coupler pin can easily be dropped into position to secure the draft members together, this result being accomplished because of the flexibility 10 of the mounting for the draft mechanism.

Another and further object of my invention is the provision of a draft means which is semi-automatic in its operation in that it requires the attention of an operator only 15 to drop the coupler pin into position after the coupling members are in proper engagement with each other, which function is performed automatically by reason of the flexibility of the mounting of the coupling members.

The dropping of the pin which is the only manual function required in the operation of my invention, can be easily accomplished mechanically from the outside of the car by 20 such simple means as will readily suggest themselves.

Another and further object of my invention is the provision of coupling means for mine cars secured to the cars in such manner that one or more of said cars which are 30 coupled together can be turned sidewise on the axis of the coupling by any suitable sort of dumping mechanism, and then returned to their normal upright position while being coupled together in a train of cars, the 35 coupling means being rotatably mounted at one end of each of the cars and said rotatable mounting being constructed so that the coupling member will return to a normal position and will so remain when the cars are 40 returned to level.

Another and further object of my invention is the provision of a mine car coupler one member of which will always be in 45 proper coupling position, that is, the coupler head will project forward in a plane horizontal to the plane of the mine car, and if the coupling shank becomes turned by the jostling of the mine car, it will automatically 50 right itself because of the shape of the coupler shank and a counterweight at the rear end thereof.

These and further objects of my invention 55 will be more fully and better understood by reference to the accompanying drawings in which

Figure 1 is a plan view of my improved invention in buffering position;

Figure 2 is a vertical side view, partially in elevation and partially in section, of the 60 device shown in Figure 1 in buffering position;

Figure 3 is a vertical sectional view on lines 3—3 of Figure 1.

Referring now specifically to the drawings and in which like reference characters refer to like parts throughout, a mine car 10 is shown having a longitudinally extending draw bar secured to longitudinal sills 11 and 11^a secured thereto in any approved manner, to which is secured, in any approved 70 manner, a female coupler head 12 as by bolts 13, 13, a filler block 11^b being provided between the sills 11 and 11^a. The member 12 at its forward end has a flared recess 14 therein with an overhanging upper portion 15 and a forwardly extending lower portion 16, and with laterally extending lips 17 and 18. The walls of the recess 14 converge until they meet at 19 to form a rounded seat for the male coupler head hereinafter described 80 which is secured to another mine car. The male coupler head engages against either the side portions 17 or 18 of the coupler head 12 if the head enters the recess 14 at an angle, or if the mine cars are on unequal 85 levels or the couplers are at unequal heights, the male coupler head strikes against either the upper or lower portions 15 or 16 of the coupler head 12 and is directed either upwardly or downwardly until it is seated 90 against the seat 19 in proper coupling relation, irrespective of ordinary curvatures and grades of track. The head 12 has a vertically extending pin opening 20 therein through which a coupling pin 21 passes so that the 95 two coupling members are held in engagement with each other by the pin 21.

Secured to a second mine car 10^a, is a coupling housing 22 composed of a pair of Z-bars 23 and 24 which form the upper portions of the coupling housing 22 and which have outwardly turned flange portions 25 and 26 which are bolted to the bottom plate 27 of the mine car and to the longitudinal sills 28 and 29 which correspond to the 105 angles which at the end of the other car 10 are designated as 11 and 11^a to which the female coupler head 12 is attached. Secured to coupler housing 22 on its inner sides is a pair of spaced U-bars 30 and 31 and which have a coupler block 32 therebetween, the said coupler block 32 being 110

held in position by angle lugs 34 and 35 bolted to the sills 28 and 29. In this way the coupling block 32 with the entire male coupler mechanism can be easily removed or replaced by removing the bolts holding the angles 34 and 35 in place. A top plate 36 is provided which is secured to the Z-bars 23 and 24 in any approved manner and so as to thoroughly enclose the coupler mechanism and provide a solid and dust-proof bottom for the car.

The coupler shank 29^a extends rearwardly of the coupler housing 22 and through a hole 39 in the block 32, the said hole 39 being flared outwardly on each of its sides to allow for vertical and lateral movement of the coupler shank 29^a in the block 32.

The hole 39 is somewhat elongated in a vertical direction and has a flat portion 40 on the bottom thereof so as to tend to bring the male coupler member to a horizontal position whenever it has become displaced through rotation, the coupler shank 29^a being flattened on its lower side so as to be in normal position upon the flattened portion 40 in the coupler block 39. The coupler shank 29^a has a head 14^a on its outer end which is adapted to enter the recess 14 and is guided into proper coupling relation by the converging walls of the female head as heretofore described. The coupler block 32 has graduated vertical recesses 41, 42, 43, and 44 in its front and rear faces with a predetermined width of straight faces or ribs 45 and 46 between same one of said ribs being formed upon each side of the coupler block 32. The width of the straight faces 45 and 46 is designed to give the springs a sufficient width of bearing face to resist vertical movement with a corresponding lack of resistance to the horizontal movement of the coupler head. When the male coupler head is moved in a horizontal plane, the springs will swing into the recesses provided for them on each side of the ribs 45-46 and as soon as the force is removed the springs will return the coupler shank back to normal position. Around the coupler shank 29^a and bearing against the coupler block 32 in buffering position of the coupler shank 29^a and against a shoulder 47 is a cup-shaped spring container 48 with a coil spring 49 therein which is proportioned for taking care of the bumping and pushing of cars. The container 48 will transmit the buffering load directly into the coupler block 32, when the spring has received a predetermined amount of compression and before the spring is compressed solid and so thus caused to set.

Mounted upon the coupler shank 29^a on the opposite side of block 32 is a spring container 50 having a spring 51 therein, which serves the same purpose and operates in the same way as the container 48

and spring 49 on the opposite side of the coupler block. A counterweight 52 is provided mounted upon the coupler shank 29^a at its rear ends into which the container 51 is seated with its lower portion extended downwardly and rearwardly to counterweight the coupler head 14^a, and to aid in righting the male coupler shank and hold it in a horizontal position.

The rear end of the coupler shank is threaded and provided with two nuts 53 and 54, by means of which the compression of the springs can be adjusted and maintained.

The male coupler head 14^a which is forged or cast as a part of the coupler shank 29^a, is shaped in accordance with the inner face of the female coupler so that it will ride into coupling position when the cars approach each other from any practical angle, either horizontally or vertically. The contour of the head and the shape of the opening in member 12 is such that the coupler head 14^a will always ride into engagement with the female coupler so that the pin 21 can be dropped into position. The hole in head 14^a is of such size and shape that it will take the pin 21 when the head 14^a has come into final position from any practicable angle. When coupled up cars within the trip are rotated around a longitudinal axis in some dumping apparatus, in order to discharge their contents the male coupler head 14^a is held more or less rigidly between the jaws of the female coupler 12. The rotation occurs between the male coupler shank 29^a and the coupler block 32. When the cars are brought back to normal, the coupler head 14^a will also return to an approximately horizontal position. The weight of the counterweight 52 and container member 50 being below the center of rotation will tend to bring the shank back to a normal position and the round coupler shank 55 is formed with a flat section throughout its length on the bottom which normally rests on the flat portion of the hole in the coupling block 32. In the process of rotation the coupling shank 29^a lifts slightly from its bearing in the coupler block 32 and in returning to normal position this operation is reversed and the flat portion of the coupler shank will seat itself on the flat portion of the coupling block so that the male coupler will return to an exactly horizontal position and stay there against ordinary displacement such as might result from jostling or jolting of the car. In going around curves or over inequalities of grade, the male coupler will pivot either vertically or horizontally in the coupler block 32 and the tension of the springs will bring it back to an axial position, both vertically and horizontally.

It will thus be understood that when the

coupling operation is attempted with one car standing on a curve and the other car approaching on a straight track or reverse curves, or if either car is on a point where 5 the grade suddenly changes, the male coupler will in every instance, engage the female coupler somewhere within its coupling range and will then be guided into a position where it will only be necessary to drop 10 the pin in order to complete the coupling.

This operation makes it necessary for the operator only to extend his arm between the cars in a space clear of all obstruction and comparatively free from danger whether the 15 cars are moving or standing, instead of lifting a heavy coupling into place as in ordinary practice which makes it necessary for the operator to throw his body more or less between the cars with a consequent danger 20 of being injured or crushed by the rounded or full car width bumpers, such as are usually provided with the ordinary type of coupling, and the space between the cars is absolutely clear except for the coupling members. 25

It would obviously be possible to lift or drop the pin by means of a properly constructed series of levers and chains extending to the outside of the car in such a way 30 that it would not even be necessary for the operator to put his hand between the cars in completing the coupling operation.

While I have described more or less precisely the details of construction, I do not 35 wish to be understood as limiting myself thereto, as I contemplate changes in form and the proportion of parts and the substitution of equivalents as circumstances may suggest or render expedient without departing 40 from the spirit or scope of my invention.

I claim:

1. Draft mechanism for mine cars comprising in combination a draw bar having a shank portion, a coupler block through 45 which the said shank extends, springs mounted upon said shank on each side of the coupler block and adapted to receive normal pulling and buffing strains, cup shaped members mounted upon the said shank within which the said springs are seated and adapted to transmit pulling and buffing strains to said coupler block when the said springs are compressed and means 50 for securing the said coupler block to a mine car.

2. Draft mechanism for mine cars comprising in combination a draw bar having a coupler head at its forward end thereof and a shank extending rearwardly therefrom, a 55 coupler block having an opening therein through which the said shank extends, springs mounted upon said coupler shank on each side of the coupler block and means for retaining the springs in normally com-

pressed relation, the said coupler block having vertically extending ribs adjacent the coupler block opening forming a seat for the said springs at one of their sides. 65

3. Draft mechanism for mine cars comprising in combination a draw bar having a coupler head at its forward end thereof and a shank extending rearwardly therefrom, a coupler block having an opening therein through which the said shank extends, 70 springs mounted upon said coupler shank on each side of the coupler block and means for retaining the springs in normally compressed relation, the said coupler block having vertically extending recesses on each side of the opening therein through which the 75 coupler shank extends whereby lateral movement of the coupler shank is permitted. 80

4. Draft mechanism for mine cars comprising in combination a rotatably mounted draw bar having a coupler head at the forward end thereof and a rearwardly extending shank portion, a coupler block having an opening therein flattened at one of its sides through which the said coupler shank 85 extends, springs located upon the said coupler shank on each side of the said coupler block, means at the rear end of said coupler shank to place the said springs under compression, the said shank having a flattened portion at the lower side thereof adapted to 90 cooperate with the flattened portion of the opening in the coupler block in the normal position of the coupler head, means for securing the draft mechanism to a mine car, and means secured to said coupler shank 95 whereby the coupler head is normally retained in a horizontal position. 100

5. Draft mechanism for mine cars comprising in combination a rotatably mounted draw bar having a coupler head at the forward end thereof and a rearwardly extending shank portion, a coupler block having an opening therein through which the said coupler shank extends, springs located upon the said coupler shank on each side of the 105 said coupler block, means at the rear end of said coupler shank to place the said springs under compression, the said shank having a flattened portion at the lower side thereof adapted to cooperate with the flattened portion of the opening in the coupler block in the normal position of the coupler head, 110 means for securing the draft mechanism to a mine car, means secured to said coupler shank whereby the coupler head is normally retained in a horizontal position, said means comprising a counterweight secured to the rear end of the coupler shank and held in 115 non-rotatable position therewith. 120

Signed at Chicago, Illinois, this 10th day 125 of March, 1922.

ANDREWS ALLEN.
